SURGICAL INSTRUMENT

Joseph Edward Held, New York, N. Y., assignor to
 American Cystoscope Makers, Inc., New York,
 N. Y., a corporation of New York

Application July 31, 1948, Serial No. 41,753

8 Claims. (Cl. 128—305)

1

This invention relates to a surgical instrument, and more particularly to such an instrument adapted to be used advantageously in endo-choledochal sphincterotomy.

It has been ascertained that acute pancreatitis may be produced by the retrojection of bile into the pancreatic duct should the ampulla of Vater become occluded by a stone. It has also been determined that spasms of the sphincter of Oddi may produce sufficient temporary constriction and obstruction of the same to enable bile to enter the pancreatic duct. Spasms of the highly labile sphincter of Oddi muscle may be produced by intense pain, drugs or other means. Obstruction of the duct by such spasms can be prevented by cutting the sphincter with the aid of the instrument of this invention, thereby eliminating a potential cause of such obstruction.

It is the primary object of this invention to provide an instrument adapted to be advantageously employed in internal surgical procedures.

The invention has for another object the provision of a surgical instrument adapted to be readily inserted to the region of and sever the sphincter of Oddi muscle.

It is a further object of the invention to provide an instrument of the character indicated that is capable of performing its intended functions in an effective and trouble-free manner.

The foregoing objects, as well as other objects, and the advantages obtainable by the practice of this invention will be readily apparent to persons skilled in the art upon reference to the following detailed description taken in conjunction with the annexed drawing, which respectively describes and illustrates a preferred embodiment of the invention.

In the drawing:

Figure 1 is a view in side elevation, partly in longitudinal cross section, of an instrument constructed in accordance with this invention;

Figure 2 is an enlarged view of the left-hand portion of Figure 1, with certain parts shown in central cross section;

Figure 3 is a view taken along line 3—3 of Figure 2; and

Figure 4 is a view taken along line 4—4 of Figure 2.

Referring to the drawing, wherein like reference numerals denote corresponding parts throughout the several views, and more particularly to Figure 1, a forceps control unit, generally indicated by numeral 10, includes a support body 12 formed with a saddle 14 at its forward end

portion and slotted, as indicated at 16. A first handle 18, preferably integral with support 12, is provided with a thumb-receiving loop 20. A second handle 22 has its upper portion disposed in slot 16 and is pivotally connected to the support by a screw 24. Handle 22 is provided with a finger-receiving loop 26 at its lower end, and is secured at its upper end to a block 28 that is slidable with respect to support 12.

5 The rearward portion of an arcuate sheath or tube 30 is positioned in and attached to saddle 14. A plug 32 closes the forward end of sheath 30. As is indicated in the various views, the plug and the immediately adjacent external portions of the sheath are rounded so as to facilitate introduction of the instrument into a body passage without excessive trauma.

The sheath is formed with a pair of diametrically opposed slots 34 and 36, the latter consisting of a forward portion of enlarged width 38 and a merging rearward portion of reduced width 40.

10 A flexible rod 42 has its major portion positioned within sheath 30. The rod has its rearward end connected to block 28 and is reciprocable along the path defined by the interior of the sheath in response to alternate forward and rearward pivotal movement of handle 22 with respect to handle 18. The forward extremity of rod 42 is slotted or bifurcated, as indicated at 44. A cutting element, such as a knife 46, having a preferably toothed cutting edge 48, registers with slot 44 in rod 42 and is pivotally connected to the rod by a pin 50. Cutting element 46 is also pivoted to sheath 30 by means of a second pin 52, the axis of which is parallel to and disposed rearward of the axis of pin 50. Each of a pair of spacer sleeves 54, concentric with pin 52, is positioned intermediate a side surface of the cutting element and the interior surface of the sheath to maintain the cutting element in the illustrated spaced relation to the sheath.

15 For the purpose of briefly outlining the operation of the instrument in a sphincter-severing procedure, it is first assumed that the parts are assembled and in the relative position shown in Figure 1. Before the instrument is placed in use, the operator inserts his thumb in loop 20 and a finger in loop 26, and urges handle 22 in a counter-clockwise direction of rotation about the axis of pivot screw 24, as viewed in Figure 1, to thereby move flexible rod 42 forwardly along the interior of sheath 30 and effect counter-clockwise rotation of cutting element 46 about its pivotal connections with the rod and the sheath, whereby

the toothed portion of the cutting element is retracted in slot portion 40.

By virtue of the construction herein illustrated and described, the sheath may be inserted through the common duct into the duodenum until it elevates the anterior duodenal wall. Handle 22 is then moved in a clockwise direction, thereby effecting corresponding clockwise pivotal movement of cutting element 46 to dispose the cutting element in open position (Figure 1). With the cutting element thus in open position, the instrument is withdrawn to a sufficient extent so that the cutting element engages the papilla. The control forceps is now actuated to impart counter-clockwise rotation to cutting element 46, thereby effecting severance of the sphincter of Oddi in one plane.

From the foregoing, it is believed that the construction, operation, and advantages of my present invention will be readily comprehended by persons skilled in the art. It is to be clearly understood, however, that various changes in the apparatus set forth above may be made without departing from the scope of the invention, it being intended that all matter contained in the description or shown in the drawing shall be interpreted as illustrative only and not in a limiting sense.

I claim:

1. A surgical instrument comprising a sheath having a slot formed therein, a rod reciprocable in the sheath, a cutting element independently pivoted to the rod and the sheath and registering with the slot, and means for imparting reciprocal movement to the rod with respect to the sheath to thereby effect corresponding movement of the cutting element about its pivotal connections with the rod and sheath.

2. A surgical instrument comprising an arcuate sheath having a longitudinal slot formed in its forward portion, a flexible rod reciprocable in the sheath, a cutting element independently pivoted to the forward portion of the rod and to the sheath and registering with the slot, and means secured to the rearward portion of the sheath and the rod for imparting reciprocal movement to the rod with respect to the sheath to thereby effect corresponding movement of the cutting element about its pivotal connections with the rod and sheath.

3. A surgical instrument in accordance with claim 2 wherein the sheath is closed at its forward end and the cutting element is pivoted to the sheath rearward of its pivotal connection with the rod when the cutting element is in retracted position with respect to the sheath.

4. A surgical instrument comprising a sheath closed at its forward extremity and having a longitudinal slot formed therein, a rod reciprocable in the sheath, the forward end portion of the rod being slotted, a cutting element registering with the slots in the rod and the sheath and independently pivoted to the rod and sheath, and means connected to the rear portions of the sheath and the rod for imparting reciprocal

movement to the rod with respect to the sheath to thereby effect corresponding movement of the cutting element about its pivotal connections with the rod and sheath.

5. A surgical instrument comprising an arcuate sheath closed at its forward end and having a longitudinal slot formed therein, a flexible rod reciprocable in the sheath, the forward end portion of the rod being slotted, a cutting element registering with the slots in the rod and the sheath and independently pivoted to the rod and sheath, and means connected to the rear portions of the sheath and the rod for imparting reciprocal movement to the rod with respect to the sheath and corresponding movement to the cutting element about its pivotal connections with the rod and sheath.

6. In an instrument of the character described, a control unit comprising a support, a first handle rigidly secured to the support and a second handle pivotally connected to the support, a sheath mounted on and projecting forwardly of the support, said sheath having a longitudinal slot formed in its forward portion, a rod slidable in the sheath, said rod being connected to the second handle and reciprocable in the sheath in response to pivotal movement of the second handle with respect to the support, and a cutting element pivoted to the forward portion of the rod and to the sheath and registering with the slot.

7. In an instrument of the character described, a control unit comprising a support, a first handle rigidly secured to the support and a second handle pivotally connected to the support, an arcuate sheath mounted on and projecting forwardly of the support, said sheath having a longitudinal slot formed in its forward portion, a flexible rod slidable in the sheath, said rod being connected to the second handle and reciprocable in the sheath in response to pivotal movement of the second handle with respect to the support, and a cutting element pivoted to the forward portion of the rod and to the sheath and registering with the slot.

8. An instrument in accordance with claim 7 wherein the forward extremity of the sheath is closed and the cutting element is pivoted to the sheath rearwardly of its pivotal connection with the rod when the cutting element is in retracted position with respect to the sheath.

JOSEPH EDWARD HELD.
